GARMENT AND COLLAR CONSTRUCTION

Elaine Goldson, Great Saughall, Cheshire,
EnglandApplication February 28, 1948, Serial No. 11,997
In Great Britain August 7, 1946Section 1, Public Law 690, August 8, 1946
Patent expires August 7, 1966

2 Claims. (Cl. 2-98)

1

This invention relates to coats, jackets, and the like garments (hereinafter, for convenience of description, referred to as "coat") more particularly for women's wear; and aims to provide such a garment which may be worn with or without a provided collar, as may be preferred.

According to my invention, the neck portion of a coat, jacket or like garment, all hereinafter included in the term "coat," for personal wear is made and finished without a collar, but between the cloth layers—i. e. between the coat cloth itself and the conventional facing—there is formed in each front portion of the neck a pocket opening wherein is secured a fastener component (or components) usually of press-stud type; and spacedly arranged around the inside of said collarless neck at a suitable distance below the edge thereof are further fastener components and for use in the combination with such a coat, as and when the wearer so desires, I provide a collar piece—usually of the same material as that of the coat—of appropriate shape and having been so severed that end portions thereof are in the form of tongues to which the co-operating components of said coat pocket fasteners are secured; also fastener components are secured on the outer side of the collar near its lower edge, these being spacedly arranged to correspond with those of the coat's neck.

Preferably said tongues are reinforced or stiffened as by means of Celluloid, rubber or other suitable resilient material.

In fitting the collar to the coat, said tongues of the former are entered into said pocket openings of the coat's neck and detachably fastened therein; the collar is also engaged by its spaced fastener components with those of the inside of the coat's neck.

I will further describe my invention with the aid of the accompanying sheet of explanatory drawings which illustrate, by way of example and not of limitation, one mode of embodying same.

In said drawings:

Fig. 1 shows the upper portion of a collarless coat, and Fig. 2 is a view of the collar.

Fig. 3 illustrates the coat and collar when detachably assembled together, but prior to the collar being turned down, and Fig. 4 is a view showing the collar when draped over the coat's neck.

It is to be noted that in Fig. 1 the pocket openings appear as if gaping, but, of course, in actual wear, the clothes layers will lie flatly against each other, so that the "splits" will not be noticeable.

10 generally designates a garment coat for women's wear which is tailored without a col-

2

lar and may be so worn, and 11, 11 indicate pocket-like openings formed between the cloth layers 12, 13 (13, 13 representing the facing pieces of the same material as that of the coat) at the respective—when the coat is donned—front neck portions and in each of which pocket openings 11 a fastener component 14 of press-stud type is sewn. Further press-stud fastener components 15 are spacedly sewn around the inside of said 10 collarless neck just below the upper edge thereof, and being of course, concealed from view when the coat is being worn without the collar.

16 denotes a collar piece made of the same cloth as that of the coat, and the end portions 15 whereof have been cut to create tongues 16^a, to each of which tongues a co-operating fastener component 14^a is sewn. Also fastener components 15^a spacedly arranged to correspond with those 15 of the coat's neck are sewn on to the outer side of collar 16 near its lower edge.

In fitting collar 16 to the coat 10, said tongues 16^a of the former provided with resilient stiffening strips 17 of Celluloid or the like, concealed between the two layers of cloth of which the collar is composed, are entered into said pocket openings 11 of the coat's neck and detachably secured therein by fasteners 14, 14^a; collar 16 is also engaged by its spaced fasteners 15^a with those 15 of the inside of the neck. The collar is 20 after attachment draped over the edge of the coat's neck, and this without becoming creased or wrinkled.

It is to be noted that application of the collar to and its removal from the coat may be quickly and conveniently effected.

What I claim as my invention, and desire to secure by Letters Patent is:

1. A garment comprising in combination a collarless coat formed at its neck portion of two 40 layers of cloth, said coat having pocket openings provided in the top of each front neck portion and between said cloth layers, fastener components mounted in each of said pocket openings, additional fastener components spacedly mounted around the inside of said neck at a suitable 45 distance below the edge thereof and a collar member having end portions thereof forming tongues each capable of entering one of said coat pockets, fastener components each carried by one 50 of said tongues for engaging the component in the corresponding pocket, and further fastener components carried on the outside of said collar and adapted for engaging the components around the inside of said coat neck, and means for stiffening said collar tongues.

2. A garment comprising in combination a collarless coat formed at its neck portion of two layers of cloth, said coat having pocket openings provided in the top of each front neck portion and between said cloth layers, fastener components mounted in each of said pocket openings, additional fastener components spacedly mounted around the inside of said neck at a suitable distance below the edge thereof, and a collar member having end portions thereof forming tongues each capable of entering one of said coat pockets, said collar being formed by two layers of material, stiffening strips positioned between said layers of collar material with each in one of said tongues, fastener components each carried by one of said tongues for engaging the component in the corresponding pocket, and further fastener

components carried on the outside of said collar and adapted for engaging the components around the inside of said coat neck.
